UNITED STATES PATENT OFFICE.

GEORGE A. KNAAK, OF OSHKOSH, WISCONSIN.

ELECTRICAL SWITCH.

1,085,920.

Specification of Letters Patent.

Patented Feb. 3, 1914.

Application filed June 10, 1912. Serial No. 702,740.

To all whom it may concern:

Be it known that I, GEORGE A. KNAAK, a citizen of the United States, and resident of Oshkosh, in the county of Winnebago and State of Wisconsin, have invented certain new and useful Improvements in Electrical Switches; and I do hereby declare that the following is a full, clear, and exact description thereof.

10 The primary object of my invention is to provide a simple, economical and effective means for energizing a spring element whereby the stored power is directed in opposite directions, the invention being particularly applicable to double-acting spring-controlled snap switches or the like.

Another object of my invention is to provide a system of actuating levers for initially producing stored power in the spring 20 or switch element whereby the spring energy imparts a quick movement in either direction to effect closing or opening of an electric circuit, which quick movement precedes the lever movement and is independent 25 therefrom.

This invention is particularly designed as a circuit controller for electric motor-driven fluid compressors whereby stored fluid pressure therefrom is predeterminedly 30 regulated, the regulation being effected through the direct influence of the fluid pressure upon a piston or other movable element which in turn operates the lever mechanism for energizing the spring-controlled 35 element that actuates the switch, said switch being preferably of the knife type.

With the above objects in view the invention consists in certain peculiarities of construction and combination of parts as hereinafter set forth with reference to the accompanying drawings and subsequently claimed.

In the drawings Figure 1 represents a 45 face view of a controller mechanism embodying the features of my invention with parts broken away and parts in section to better illustrate certain structural features; Fig. 2, a detailed cross-section, the section being indicated by line 2—2 of Fig. 1, and Fig. 3, a detailed cross-section of the make and break switch members, the section being indicated by line 3—3 of Fig. 1.

Referring by characters to the drawings, 55 1 represents a fluid chamber that is provided with a diaphragm 2, which diaphragm

carries a plunger 3 that constitutes a movable member adapted to be actuated under the influence of a fluid in one direction and a spring in the opposite direction. The 60 fluid chamber is also provided with a supply throat 1' which is threaded for the reception of a pipe that serves as a conductor from a fluid storage tank which is supplied with fluid from a compressor. All of this 65 mechanism forms no part of my invention and is therefore not shown. The plunger 3 is arranged to engage the long arm of a bell-crank lever 4, which lever is fulcrumed to a bed-plate 5 that carries the controller 70 mechanism together with the diaphragm chamber, the short arm of the bell-crank lever engages one arm of a master lever 6, which lever is also fulcrumed to the plate, its opposite arm terminating with a forked 75 head, the tangs 6' of which each carry tappet screws 7 that extend toward each other and are adapted to engage an ear 8 that projects outwardly from a short arm of a spring actuating lever 9, the same being also fulcrumed to the head-plate. The long arm of 80 the spring-actuating lever carries a split-stud 10, into the kerf of which is fitted a normally bowed leaf-spring 11, the stud being in engagement with the center portion 85 of the leaf spring. The ends of the leaf-spring are shouldered and provided with reduced ears 11', which ears extend through slots that are formed in the ends of yieldable arms 12, 12 of a bracket member, which 90 member is provided with a foot 13 that is adjustably attached to the bed-plate 5 by screws that engage slots in said foot. The arms 12 of the bracket are formed from spring metal whereby yield at their free 95 ends is had, the tension or resistance to yield of the arms being predeterminedly regulated by the gage of the metal. The end of the long arm of the spring-actuating member extends beyond the stud in the form of 100 a tappet finger 9', which tappet finger is adapted to alternately engage either one of a pair of jaws 14 that form part of a tumbler 15, which tumbler is also fulcrumed to the bed-plate. The tumbler has secured 105 thereto a flat tail-piece 16 that is stamped or otherwise formed from fiber or other insulating material. The tail-piece projects between a pair of parallel contact springs 17, 17', the ends of which are adapted to close 110 an electric circuit, said springs being insulated from each other and suitably connect-

ed to conductor wires as shown. Movement of the tumbler is limited in either direction by stop-pins 18 which engage the tumbler jaws when said tumbler is actuated.

5 The lower arm of the master lever is connected to one end of a heavy coiled spring, the opposite end of which coiled spring is rigidly secured to the bed-plate 5 by a screw or other element, it being apparent that said

10 spring can be adjusted as to tension, whereby the controlling apparatus as a whole can be predeterminedly set so as to act under the influence of fluid at any desired pressure.

15 In the operation of my device when the fluid in the chamber 1 has reached the pressure to overcome the coiled spring 4', it is apparent that the movable member or plunger carried by the diaphragm will act upon

20 the system of levers and the parts being in the position shown in Fig. 1, the upper arm of the lever will move from left to right and in its travel the tappet screw 7' carried by said arm will engage the short arm of the bell crank lever 9. Hence the long arm of

25 said lever will move downwardly in the direction indicated by the arrow and through its engagement with the leaf-spring said leaf-spring will be caused to gradually and

30 slowly straighten out, the yieldable arms 12 of the bracket permitting lengthening of said leaf-spring. At the instant that the leaf-spring has traveled past an imaginary line intersecting its end it is apparent that

35 the stored power in said spring will exert itself and said spring will thus quickly bow outwardly in the opposite direction from that shown. This quick movement of the leaf-spring will cause the tappet finger 9'

40 to engage the lower jaw 14 of the tumbler, whereby said tumbler is rocked upon its fulcrum to cause the insulated tail-piece thereof to travel upwardly and wedge the contact spring members 17, 17' apart, thus

45 breaking the circuit. It should be understood that this electrical circuit, which is controlled by the spring members, is connected to a motor not shown, through which motor power is applied to a compressor.

50 Hence it is apparent that when the circuit is broken as just described, that the compressor

will be thrown out of operation and no further storage of fluid will take place until such time as the pressure in the storage tank has been reduced sufficiently to permit retraction of the movable or plunger member 3, which retraction is caused through exertion of the coiled spring 4' upon the master lever 6. By this arrangement it is also apparent that the spring member when applied to a switch will cause the same to cut in or out instantaneously and thus eliminate the detrimental effects of a slow moving cut-out member, the stored spring energy being exerted positively in both directions whereby the movable element of the switch, which in this instance is a tumbler, is acted upon. It will also be observed that the stored power in the switch is to a great extent determined by the flexibility of the bracket arms 12, which arms serve to buckle or bow the leaf-spring in opposite directions to accomplish the desired movements.

I claim:

1. An elliptical switch of the character described comprising a pivoted tappet-lever, a bow-spring secured to said lever and having its ends projecting in opposite directions, and a fixed bracket having yieldable arms in interlocked engagement with the bow-spring ends, the arms being adapted to spread coincident to flexure of the bow-spring in either direction. 75

2. An electrical switch of the character described comprising a pivoted tappet-lever having a stud extending therefrom, a bow-spring secured to the stud and having its ends projecting in opposite directions, and a fixed bracket having yieldable arms in interlocked engagement with the bow-spring ends, the arms being adapted to spread coincident to flexure of the bow-spring in either direction. 80 85

In testimony that I claim the foregoing I have hereunto set my hand at Oshkosh, in the county of Winnebago and State of Wisconsin, in the presence of two witnesses. 90 95

GEO. A. KNAAK.
